UNITED STATES PATENT OFFICE.

JESSE L. LAW, OF MOUNT VERNON, NEW YORK.

DOMINO.

SPECIFICATION forming part of Letters Patent No. 295,023, dated March 11, 1884.

Application filed August 8, 1883. (No model.)

To all whom it may concern:

Be it known that I, JESSE L. LAW, a citizen of the United States, residing at Mount Vernon, in the county of Westchester and State of New York, have invented new and useful Improvements in Dominoes, of which the following is a specification.

This invention relates to improvements in dominoes; and it consists of a domino having a base of wood or other suitable material, provided with a face or covering of celluloid or other similar material, said face or covering having pressed into or upon its spots or marks, as hereinafter more fully set forth. A back of similar material as that constituting the face may be applied to the base. A pivotal pin, as also a raised border or edge, may be formed or embossed or pressed on the face. The face of the domino may also have the denominations or pictures of playing-cards between and around its spots, so that the dominoes can also be used for a game of cards.

Figure 1 represents a face view of a domino made in accordance with my invention. Fig. 2 represents a transverse section in the plane $x x$, Fig. 1. Fig. 3 represents a modified form of construction. Fig. 4 represents a transverse section in the plane $y y$, Fig. 3.

Similar letters indicate corresponding parts. In the drawings, the letter A designates a base or block of wood or other suitable material. To the upper side of the block A is attached a face, B, of celluloid, xylonite, coralline, chrolithion, vulcanized rubber, or other suitable material which can be raised, embossed, impressed, or depressed by pressure with or without heat beyond the ordinary temperature of the atmosphere, according to the nature of the material. The back of the block or base A may also be covered by a similar layer or back, C, of like material as that constituting the face. In the case shown in Figs. 1 and 2 the spots or marks D of the domino are embossed or raised above the surface of the face B. A raised border, E, and a raised cross-bar, G, may be formed on the face B. The border E is higher than the spots or marks D, so that the dominoes, when being shuffled on a table or board with their faces down, will not have the spots or marks D chafed or scratched. A pivotal pin, H, may

also be provided, which rises above the top of the border or rim E and cross-bar G, which pin H offers a further protection to the face when the domino lies with its face down, and also serves as a pivot for the domino to spin on while being shuffled. In the case shown in Figs. 2 and 3, the spots or marks D, instead of being raised or embossed on the face B, are depressed or sunken in the material of the face. These depressions or indentations D do not pass entirely through the material of the face B, so as to expose the base A, but pass only partly into said face material, and said depressions or indentations may be colored in any desired manner. The face of the domino may be further provided with denominations or pictures of playing-cards, as shown—as, for example, outlines or sketches of spades, clubs, hearts, or diamonds—so that the dominoes may be used for playing a game of cards. In adapting the dominoes for this purpose—for example, to form a euchre-deck—the nine and ten spots of the dominoes may be used for the nine and ten spots of a certain color, while the remaining dominoes may have formed on them pictures or denominations indicating their character as playing-cards.

The manufacture of the dominoes is accomplished as follows: A base-slab of wood or other suitable material is scored with a knife or otherwise roughened on its face, and, if desired, also on its back, so as to allow the facing B and backing C to readily adhere to the slab. Upon the base-slab thus prepared is placed the material for the face B, and if a backing, C, is desired, the material for the same is placed against the back of the base-slab. The layers thus superposed are now placed with the back on a smooth steel plate, and over the layers is placed a die, having upon its surface marks or spots, figures, borders, dividing-bars, and pivotal-points, or any of these features, and which are either embossed on the die or sunk into the same, according as they are to be depressed into or embossed on the face B. The die and plate, with the interposed materials, are then placed in a press, which is heated by steam or other suitable means, and are exposed to pressure in presence of heat, whereby the face material and backing are pressed firmly against the

wood and adhere to the surface thereof. Additional adhesiveness is secured between the face and back by applying a suitable cement to the surfaces which are to be united. The cement which I prefer to use for this purpose is made from the same material as that from which the face is composed, a cement made from celluloid being employed in connection with a face made of that material, and so on in respect to the other materials employed; but I do not wish to restrict myself as to the kind of cement to be used. In making such cement I use suitable solvents, which are well known as solvents for the respective materials employed.

To make the cement, the xylonite, celluloid, or other material is cut into fine chips or reduced in size, so as to readily dissolve. The chips are placed in a tin pail or other suitable receptacle, and alcohol poured upon them in sufficient quantity to dissolve the material. Gum-camphor is added in sufficient quantity to give the solution about the consistency of cream, or a slightly thinner consistency, the gum-camphor being added when the alcohol has dissolved the material. When the solution or mixture is about the consistency of cream, it is ready for use, and may be applied to the wood with an ordinary paint-brush in the same manner as paint is applied. The plate and die while in the press are gradually allowed to cool, and when cool the finished slab is taken out, the blocks constituting the various dominoes are sawed apart, and the exposed sides of the base-blocks A are colored to suit the taste with any suitable coloring-matter, so as to match with the color of the face and back. The back C may be left off and the back of the base A colored instead.

The die is not shown in the drawings, the construction of such dies being known, having been shown in the United States Patent of Shepherd, No. 274,668, of March 27, 1883. I would further state that I do not claim a domino having a back and a face of celluloid or other similar material recessed to show the spots or marks through the surfacing, as in my domino the recesses do not pass through the facing; neither do I claim the inventions described in United States Patents No. 162,072, dated April 13, 1875, and No. 273,559, dated March 6, 1883.

Instead of forming all the dominoes at once on a slab, and then sawing the finished slab into blocks, it is obvious that the single blocks may be first cut or shaped, and then the dominoes struck up singly; but I prefer the former method.

My invention also embraces the covering of the base A entirely with the coating of celluloid, xylonite, coralline, chrolithion, or vulcanized rubber, so that it shall be inclosed or incased, top and bottom and on all sides, by such coating. For this purpose a sectional die for each domino must be employed, one section receiving and forming the body of the domino, and the other section the face.

What I claim as new, and desire to secure by Letters Patent, is—

1. A domino consisting of a base, A, of wood or other suitable material, provided with a face or covering, B, of celluloid or similar material—such as xylonite, coralline, or chrolithion, or of vulcanized rubber, said face or covering having pressed into or upon it spots or marks D, substantially as set forth. 75

2. A domino consisting of a base, A, of wood or similar material, provided with a face or covering, B, and with a back, C, of celluloid, xylonite, coralline, chrolithion, or similar material, or of vulcanized rubber, said face or covering having pressed into or upon it spots or marks D, substantially as set forth. 80

3. A domino consisting of a base, A, of wood or similar material, provided with a face or covering, B, of celluloid, xylonite, coralline, chrolithion, or similar material, or of vulcanized rubber, said face or covering having pressed into or upon it spots or marks D, and being provided with a pivotal pin, H, substantially as set forth. 85

4. A domino consisting of a base, A, of wood or similar material, provided with a face or covering, B, of celluloid, xylonite, coralline, chrolithion, or other similar material, or of vulcanized rubber, said face or covering having pressed into or upon it spots or marks D, and being provided with a pivotal pin, H, and with a raised border or edge, E, substantially as set forth. 90

5. A domino provided on its face with a raised rim, E, and a pivotal pin, H, said point rising above the level of the upper edge of said rim, as shown and described. 100

6. A domino provided on its face with the denomination or pictures of playing-cards between and around its spots, as shown and described. 105

In testimony whereof I have hereunto set my hand and seal in the presence of two subscribing witnesses.
